Patented Feb. 1, 1921.

UNITED STATES PATENT OFFICE.

EDWARD T. CURRAN, OF DETROIT, MICHIGAN.

RADIATOR.

1,367,023.

Specification of Letters Patent.

Patented Feb. 1, 1921.

Application filed June 6, 1918. Serial No. 238,427.

To all whom it may concern:

Be it known that I, EDWARD T. CURRAN, a citizen of the United States, residing at Detroit, county of Wayne, State of Michigan, have invented a certain new and useful Improvement in Radiators, and declare the following to be a full, clear, and exact description of the same, such as will enable others skilled in the art to which it pertains to make and use the same, reference being had to the accompanying drawings, which form a part of this specification.

This invention relates to radiators for use in connection with steam or hot water heating installations, and relates particularly to radiators for this purpose in which the radiator sections are made up of stampings from sheet metal welded together to form a tubular structure, and the sections mounted in juxtaposed relation upon a tube or tubes passing through openings at one or both ends of the sections, and connected in circulation by perforations in the tube or tubes communicating with the respective sections and whereby the radiator is connected in circulation with a steam or hot water supply.

It is the object of the invention to improve the general construction of radiators of this character whereby the flow of the heating medium will be facilitated and the forming of pockets obviated, facilitating the complete emptying of the radiator sections of waters of condensation when utilized as a steam radiator, or the complete emptying of the water therefrom when used in connection with a hot water heating installation and thereby increasing the efficiency of the radiator.

It is a further object of the invention to so arrange the induction and eduction pipes of the radiator that when utilized in connection with a steam heating installation the initial flow of steam will tend to force any waters of condensation therefrom which may have collected in the radiator sections and cause the flow of steam through and the heating of all of the radiator sections simultaneously, and when used in connection with a hot water heating installation to cause simultaneously the flow of the heated water to and eduction of the cold water from all of the sections, instead of successively through the sections.

Other objects and advantages will herein- 55 after appear.

In the drawing accompanying and forming a part of this specification Figure 1 is an end elevation of a radiator constructed in accordance with my invention. 60

Fig. 2 is a sectional side elevation of a radiator showing the embodiment of my invention.

Fig. 3 is an elevational view looking at 65 the side of a radiator section.

Fig. 4 is an enlarged sectional view of the lower portion of one of the radiator sections looking at the end thereof to show the connection of the section with the ingress pipe for the heating medium. 70

Fig. 5 is an enlarged sectional side elevation of the lower portion of the radiator shown in Fig. 2 to illustrate the relation of the pipe for the ingress of the heating medium and the connection thereof to the 75 radiator sections; and

Fig. 6 is a sectional view of one of the radiator sections taken substantially on the line $x-x$ of Fig. 1 to show the cross sectional shape of the radiator sections. 80

Similar characters of reference designate like parts throughout the different views of the drawing.

In carrying out the invention the radiator is built up of a number of tubular sections 85 assembled in juxtaposed relation in accordance with the desired size of radiator similar to the prevailing practice, and shown in the drawing as consisting of six sections or units. Each of the radiator sections is made up of a pair of similarly shaped members A and B stamped from sheet metal of any desired cross sectional shape and in the present instance of the cross sectional shape shown in Fig. 6, whereby as the two sections are 90 placed together they will contact adjacent the lateral edges and at which point they are welded together, and intermediate portions extending longitudinally of the members contacting, as shown at D, D, and at 100 which point the sections are secured together as by riveting or spot welding, the longitudinal portions not only serving as strengthening ribs but forming a three column radiator section, or three passages for the 105 flow of the heating medium. Each of the members A, B of the radiator sections are provided with perforations or openings E,

- preferably circular in form, at opposite ends and so arranged that when the members are brought and welded together these openings will be in axial alinement with a portion of 5 the circumferential wall of the openings tangent to the inner surface at the lowest and highest point in a radiator section, as clearly shown in Figs. 1 and 4 for a purpose to be hereinafter described.
- 10 A pipe F for the inlet of the heating medium passes through the lower openings of sections and upon which pipe the radiator sections are mounted in predetermined spaced relation and fixed thereto in steam 15 or water tight connection as by welding. The pipe F is of such length as to accommodate the number of sections which are to constitute the radiator. One end of the pipe is threaded for connection to a source of supply of the heating medium and the opposite end is closed by suitable means, or the perforation at the lower end of the outermost member of the last section of the radiator, which is at the left as shown for instance in 20 Figs. 2 and 4, being unperforated at the lower end and against which the end of the pipe F may abut and close said end of the pipe. The lower portion of the wall of the pipe F is cut into or perforated, as shown in 25 Fig. 4, at points to come in line or register with the respective radiator sections to be in circulation therewith. These openings are of progressively increasing area or size from the entrance end to the opposite extremity 30 of the pipe; that is, the opening for the first section as viewed from the right of Figs. 2 and 5 is comparatively small, as shown at g, and the openings progressively increasing in size as shown at g', with the largest opening 35 at the extremity of the pipe or opening into the last section at the extreme left as viewed from Figs. 2 and 5. By this arrangement the incoming heating medium, or the greater portion thereof, taking the course of 40 least resistance will pass out through the largest opening at the extremity of the pipe and in communication with the section at the left, and as the pressure of the heating medium passing out through the perforations or openings of the pipe in communication 45 with the other sections will be less than the pressure of the heating medium discharged from said large opening any waters of condensation in the lower portion of the 50 radiator will be caused to flow or be drained from the radiator, and this is particularly true when a single pipe system is used as in a certain type of steam heating installation. Furthermore, by this arrangement of having 55 the outlet for the heating medium at the lowermost part of a radiator or radiator section the heating medium is caused to flow through and heat all of the sections of the radiator simultaneously.

For the egress of the heating medium, as 65 in a hot water heating installation, a pipe F' engages in openings E at the ends of the radiator sections opposite to the pipe F, and shown in the drawing at the top, secured to the sections in water or steam tight connection 70 the same as the pipe F. This pipe is also provided with cut outs or perforations to connect the same in circulation with the radiator sections, the egress or outlet end of the pipe being at the end opposite to the 75 ingress end of the pipe F and threaded for connection in circulation with the source of the heating medium, as shown at the left of Fig. 2. The openings in this pipe are also of progressing size but the opening of 80 smallest size is adjacent the outlet end of the pipe, as shown at g'', and progressively increasing in size to the opposite end, as shown at g'. The end of the pipe opposite to the threaded end is closed by abutting 85 against the unperforated outer member of the radiator section at the extreme right as viewed from Fig. 2. By this arrangement the heating medium entering the pipe F the greater portion of which will tend to flow 90 through the largest opening at the extremity of the pipe taking the course of least resistance will pass up through the end section at the left, and as the outlet from this section or connection thereof with the pipe 95 F' is restricted it will tend to force any air out of said section in a steam heating installation and retard the flow of steam and place the steam therein in compression the 100 excess pressure facilitating the discharge of waters of condensation from the pipe F as hereinbefore set forth and causing the steam with greater force or pressure to be discharged through the other connections between the radiator connections and pipe. 105 By the arrangement of the perforations in the pipes F and F' the pressure of the heating medium in the radiator sections is balanced. By the arrangement of the larger perforation in the pipe F opposite to the small perforation in the pipe F' and then progressively decreasing the perforations in the pipe F from the larger opening, as 110 shown, and increasing the size of the successive openings in the pipe F' from the smallest at the discharge end of the pipe F', a substantially even and uniform pressure is maintained at all times in the radiator sections. 115

A radiator constructed as described may 120 be supported in any conventional manner, and is shown as supported by legs H, the legs being arranged or of such size relative to each other that the one end of the radiator will be slightly higher than the other 125 end thereby giving a slight inclination to the radiator facilitating the discharge of the waters of condensation from the radiator.

when utilized in a steam heating installation, and the draining of all the water from a radiator in a hot water installation.

What I claim is:

1. In a radiator of the class specified, a series of hollow sections, and an inlet pipe for the heating medium passing through the lower portion of the successive sections, said pipe having outlets opening into each of the radiator sections tangent with the inner surface of the lowermost part of the radiator sections and said openings for successive sections increasing progressively in size in the direction of travel of the heating medium for the purpose specified.
2. In a radiator of the class specified, a series of hollow sections, and an inlet pipe for the heating medium passing through the lower portion of successive sections having outlet openings, one opening into each of the radiator sections, said openings leading into the lowermost part of and progressively increasing in size in the successive section in the direction of flow of the heating medium, and an outlet piping passing through the upper portion of and in connection with the successive sections for the purpose specified.
3. In a radiator of the class specified, a series of hollow sections, an inlet pipe for the heating medium passing through one end of the sections and having openings one leading into each of the sections and progressively increasing in size in the successive sections in the direction of flow of the heating medium, and an outlet pipe passing through the opposite ends of the sections having openings one in communication with

each of the sections and progressively decreasing in size in the successive sections in the direction of flow of the heating medium 40 for the purpose specified.

4. In a radiator of the class specified, a series of sections each section having an inlet in communication with the source of the heating medium, and an outlet pipe passing 45 through one end of said sections having openings one in communication with each of the sections, said openings progressively decreasing in size in the successive sections to the outlet end of the pipe and being tangent 50 with the inner surface of the uppermost part of the radiator sections for the purpose specified.

5. In a radiator of the class specified, a series of hollow sections consisting of similarly formed sections welded together at the edges; an inlet pipe for the heating medium passing through one end of the sections having openings leading into the lowermost portion of and progressively increasing 60 in size in the successive sections; and an outlet pipe passing through the opposite ends of the sections one in communication with each of the sections and leading from the uppermost portion of the sections, said 65 openings progressively decreasing in size in the successive sections in a direction with the progressive increase in the size of the openings of the inlet pipe for the purpose specified.

In testimony whereof, I sign this specification.

EDWARD T. CURRAN.
